W. H. DEAN,
SNOW MELTER FOR RAILWAYS,
APPLICATION FILED APR. 3, 1917.

Patented Oct. 23, 1917.

UNITED STATES PATENT OFFICE.

WILLIAM HENRY DEAN, OF SIOUX CITY, IOWA.

SNOW-MELTER FOR RAILWAYS.

1,244,300.

Specification of Letters Patent. Patented Oct. 23, 1917.

Application filed April 3, 1917. Serial No. 159,463.

To all whom it may concern:

Be it known that I, WILLIAM H. DEAN, a citizen of the United States, and a resident of Sioux City, in the county of Woodbury 5 and State of Iowa, have invented a new and Improved Snow-Melter for Railways, of which the following is a full, clear, and exact description.

My invention relates to snow melting 10 means adapted to be employed on the front of a locomotive, car or the like, capable of supplying a heated fluid in the form of steam or hot air for example.

Objects of the invention are to provide a 15 snow melter having means to effectively utilize the heat of the steam or other fluid in melting the snow in advance of the locomotive, motor or car, to provide for variously disposing of the resulting water whereby to 20 allow the same to run off as the snow melts, or to discharge the water to either side of the track at the top of the melter, so that it may result in the freezing of the snow on sides of the track to prevent it from drifting; and 25 to make provision for delivering the water to the tender or to the boiler of a locomotive equipped with a melter.

An object also is to provide a catch basin 30 for the water resulting from the melter, and to so arrange the pipes conducting the melting fluid that the fluid may be so directed as to prevent the clogging of the outlets leading from the basin.

The invention also has for objects to pro- 35 vide a hood on the melter arranged to aid in retaining the heat from the melting fluid and to construct the hood and the main body or back of the melter in a form to insure and provide a cleared cut widening at the top 40 whereby to insure a proper clearance for the locomotive or cars and whereby to minimize the possibility of snow from the banks or side walls of the cut sliding or drifting to the cleared track.

Other objects of the invention, as well as 45 its advantages, will more clearly appear as the description proceeds.

Reference is to be had to the accompanying drawings forming a part of this specification in which similar characters of reference indicate corresponding parts in both the views.

Figure 1 is a diagrammatic side view of the locomotive with my invention in one

form in side elevation and it will be understood that the illustration simply is given as an example of one embodiment;

Fig. 2 is a transverse vertical section on the line 2—2, Fig. 1; in this figure the steam pipes are indicated in dotted lines while a 60 similar showing of the water pipes is omitted in the interest of clearness;

Fig. 3 is a plan view of my improved snow melter, the hood being broken away, said view showing diagrammatically certain 65 parts of a locomotive.

In carrying out my invention in the form illustrated the improved melter is formed with an inclined back structure 10 adapted to be positioned in front of a locomotive, car 70 or the like so as to incline upwardly and rearwardly. Side flanges 11 are produced on the back 10 and a hood 12 is secured to said flanges by bolts 13 or other suitable means. In the back 10 an opening 14 is 75 produced and so located as to be directly in front of the headlight of the locomotive. At the said opening 14 a closure 15 is provided having means whereby it may be opened or closed by the engineer in the cab 80 or by an attendant standing at the pilot of the locomotive. As shown the closure is formed with a lever arm 16 to which a pull cord 17 is attached and extends to the cab of 85 the locomotive.

In the rear of the back 10 I provide a system of pipes for the melting fluid. In the example shown an upright pipe 18 is provided which has a connection as at 19 with the locomotive boiler near the top thereof to 90 receive steam therefrom. A multiplicity of nozzles 21 extend through the back 10 to the front thereof, the nozzles being variously disposed over the surface of the said back. Advantageously the nozzles are in transverse 95 series and lead from branch pipes 20 connected with the pipe 18 for the most part, and in case of the uppermost pipes 20 connecting with the upright branch pipe 25 on said pipe 18. Controlling valves are provided in the system of steam pipes, there being valves 22, 23 in the branch pipe 25 and a valve 24 in pipe 18 between the same and the boiler connection to cut off the lower series of nozzles while the pipes 22, 23 control the nozzles connected with the pipe 25. 100 105

A catch basin 26 is provided at the bottom of the back 10 at the front whereby to

receive the water resulting from the melted snow. Lateral outlets 27 are formed in the hood 12 to permit water to flow outward from the catch basin to the sides of the track 5 and said outlets are controlled by suitable valves, gate valves 28 being shown.

Provision is made for pumping the water from the catch basin and utilizing the same or causing it to be directed to either side of 10 the locomotive above the same. For the purpose a suction pipe 29^a leads rearwardly from the basin and connects by a pipe 29 in the rear of the back 10 with a pump 30 mounted on the pilot or equivalent support. The pump may be operated in any 15 suitable manner. As here conventionally shown a steam pipe 30^a leads from the valve chest of the engine. The discharge pipe 31 of the pump may have connections 20 variously disposed, there being a pipe 32 connected with the boiler to utilize the resulting water as feed water. In order that the water may be directed to the tender B a pipe 34 leads to said tender along the top of the 25 locomotive and cab, it being understood that said pipe in practice will include hose sections if the same are required for convenience. The pipe 34 connects by an upright branch 31^a with the discharge pipe 31 of 30 the pump and is controlled by a valve 35 when the water is not required for the tender. As when the latter is full, for instance, the water may be directed to either 35 side of the track through nozzles 36 which are oppositely disposed above the valve 35, the nozzles being controlled by a two-way valve 37.

The structure is provided with wheels 38 which are suitably mounted as in brackets 40 39 on the catch basin at the forward end and there may be a ramp 40 on the catch basin in front of the said wheels. In order to prevent clogging of the outlets 27, 29^a by snow certain of the nozzles 21 are directed 45 downwardly at their outlet ends, as at 41, whereby the steam or other hot fluid issuing therefrom will be directed toward the catch basin.

It will be observed from the Figs. 2 and 3 50 that the hood 12 flares in an upward direction, as does also the back 10, so that the clearing or cut produced in the snow will flare upwardly to minimize the possibility of the snow from the banks or walls 55 falling or drifting to the cleared track.

By the described means it will be seen that not only is the melting fluid effectively utilized in melting the snow but the resulting water may be variously utilized.

60 I wish to state in conclusion that although the illustrated example constitutes a practical embodiment of my invention I do not limit myself strictly to the mechanical details herein illustrated, since manifestly 65 the same can be considerably varied with-

out departure from the spirit of the invention as defined in the appended claims.

Having thus described my invention, I claim as new and desire to secure by Letters Patent:

70 1. A snow melting apparatus including a back structure adapted to be disposed in front of a locomotive or car, means to direct a melting fluid to the front of said structure at various points over the surface 75 thereof, a catch basin on the said back at the bottom thereof to receive the water resulting from the melted snow, said basin having an outlet for the water, means to discharge the water from the basin, and a 80 front hood on the said back structure.

2. A snow melting apparatus including an inclined back structure adapted to be positioned in front of a locomotive or car, a system of pipes behind said structure 85 adapted to be connected with a hot fluid supply, a hood on said structure at the front, a series of nozzles leading from said pipes through said structure to the interior of the hood, at various points, a catch basin 90 at the bottom of said structure to receive the water resulting from the melting snow, and a means to draw off the water from the basin to the rear of the back structure.

95 3. A snow melting apparatus adapted to be positioned on the front of a locomotive or a car, and including a back structure, means to cause a melting of snow in front of said structure, a catch basin at the bottom of said structure to receive the result from the melting snow, and a water distributing system in the rear of the said structure and connected with said basin to draw off and distribute the water.

100 4. A snow melting apparatus adapted to 105 be positioned on the front of a locomotive or car and including a back structure, means to cause a melting of snow in front of said structure, a catch basin at the bottom of said structure to receive the water resulting from the melting snow, means connected with said basin to draw off the water, distributing pipes leading in different directions from said means to variously direct the water, and valves controlling said pipes to determine the direction of the water discharge.

110 5. A snow melting apparatus adapted to be positioned on the front of a locomotive or the like and including a back structure, means to cause a melting of snow in front 120 of said structure, a catch basin at the bottom of said structure to receive the water resulting from the melted snow, a pump connected with the said basin to draw water therefrom and valve controlled distributing 125 pipes connected with the pump discharge, said pipes including an upwardly extending pipe, a pipe directed rearwardly from the first pipe and adapted to deliver water to a tender and oppositely disposed lateral 130

pipes above the second pipe to discharge the water to either side of the track when the tender is filled.

6. In a snow melting apparatus the combination of snow melting means adapted to be positioned in front of a locomotive or the like, means to connect said first means with a locomotive to receive steam therefrom, a catch basin positioned to receive the water resulting from the melted snow, a pump connected with said basin to draw water therefrom, and a pipe connected with the pump discharge and adapted to deliver water to the tender of the locomotive.

7. In a snow melting apparatus a structure adapted to be positioned in front of a locomotive and including a back, snow melting means associated with said back, means to direct heat to the front of said back, said back having an opening located to correspond with the position of a locomotive headlight, a closure for said opening, and means to control said closure from the rear of said back.

8. A snow melting apparatus including a structure adapted to be positioned in front

of a locomotive or car, and having an inclined back receding from the lower end toward the top, a multiplicity of nozzles variously disposed at different elevations on said receding back, means to conduct a heating fluid to said nozzles, and a heat retaining hood over said structure and nozzles.

9. A snow melting apparatus including a structure adapted to be positioned in front of a locomotive or the like and having a back, a catch basin at the lower end of said back and extending forwardly therefrom, nozzles on the back positioned to discharge a heated fluid at the front thereof, certain of the nozzles being directed downwardly toward the catch basin, and means to conduct a heated fluid to said nozzles.

10. A snow melting apparatus adapted to be positioned in front of a locomotive or the like and having an inclined back, means to direct heat to the front of said inclined back and a hood on said back at the top and sides, the said hood at the sides being flared upwardly.

WILLIAM HENRY DEAN.
